JOURNAL BOX PACKING

Robert J. Harkenrider, Winona, Minn., assignor, by direct and mesne assignments, to Miller Lubricator Company, Winona, Minn., a corporation of Minnesota

Application March 26, 1954, Serial No. 419,029

6 Claims. (Cl. 308—243)

Conventional journal box packing is waste threads of wool or cotton, or both, specified by A. A. R. Mechanical Division Manual A-905, and the standard practice of applying it to a journal box is specified by the same manual L-34.

The material and its application to journal boxes has been in common use for many years attended by many objections and difficulties. The increased speed and mileage of freight cars has so multiplied those things as to result in an emergency for different and better journal box packing.

The principal object of this invention is to overcome the past difficulties and to obtain substantial uniformity of packing and lubrication with freedom from waste grab, hot boxes, etc.

Generally speaking, this is accomplished by providing packing in packages of uniform size and other characteristics, and that are readily installed in the journal boxes in proper relation to the journal and the oil cellar.

Each package includes a loop of fabric or sheet as a carrier, a uniform layer of waste or yarn on the loop having threads interlaced with or through it and made fast to it, and a resilient core having a high compression factor in the loop distending it and furnishing it with appropriate pressure to apply the waste to the journal.

The best way to get a uniform layer of waste for an applicator is to card the waste and interlace it with a fabric or other sheet as or just after it is delivered from the carding machine or waste puller, although other machines will feed waste or yarn in a usable layer for interlacing it with the fabric.

Interlacing well done will fasten most of the waste threads against being pulled out by the journal, but additional fastening with an adhesive on the inside of the carrier adds an important and desirable factor of safety against waste grab, and also adds an oil barrier to form a reserve pool of oil directly beneath the journal.

Heavy, open weave cotton cloth, similar to laundry bag cloth, makes a good carrier for journal box waste. The main fabric may be supplemented by a thin sheet including or receiving the adhesive.

A variety of woven or sheeted materials will serve for the carrier in whole or in part, and many fibers laced or interlaced through or with the carrier and made fast with adhesive will serve; but a loop of open weave cotton on the order of laundry bag cloth having a layer of journal box waste outside and inside with the threads interlaced through and made fast with an oil resistant adhesive on the inside of the loop is preferred.

Further objects and advantages of the invention will be apparent as the description is read in connection with the accompanying drawings, in which:

Fig. 1 is a cross section through a journal box and an axle journal equipped with a packing embodying the invention;

Fig. 2 is a longitudinal section through the journal box and a packing along the axis of the axle;

2

Fig. 3 is a perspective view of one form of package packing embodying the invention;

Fig. 4 is an enlarged section of the basic laminated material for the envelope;

5 Fig. 5 is a plan view of Fig. 4, parts being broken away to show the different characteristics of the several layers;

Fig. 6 is a perspective view of one form of resilient core;

10 Fig. 7 is a perspective view of another form of resilient core;

Fig. 8 is a broken view indicating one method of fastening the envelope to the core;

Fig. 9 is a perspective view of one of the strips used in Fig. 8;

Fig. 10 is a perspective view of a strap or handle used with the package;

Fig. 11 is a cross section of an alternative form of core;

20 Figs. 12 and 13 are cross sections through journal boxes equipped with packing embodying this invention, Fig. 12 having a resilient core like that shown in Fig. 6 and Fig. 13 having a resilient core like that shown in Fig. 7; and

Figs. 14 and 15 are cross sections similar to Figs. 12 and 13 including an alternative form of envelope.

But these drawings are for the purpose of illustrative disclosure only, and are not intended to impose unnecessary limitations on the claims.

In Figs. 1 and 2, 10 indicates generally a conventional journal box on a conventional axle journal 11 with a packing generally indicated by 12 in place between the lower portion of the journal and the bottom of the journal box in what is commonly referred to as the oil cellar of the journal box.

35 30 In one way of making the package or packing embodying this invention, a rectangular blank of laminated waste blanket is formed into a loop as indicated at 13 (Fig. 3) with its end portions brought together and made fast at 14. The edges of the blank are bound as indicated at 40 35 15, which may be done by putting it through an edging or edge stitching machine.

Such a loop or sub-assembly 13 receives a resilient core 16 by which the blanket material is distended and held in place between the axle journal and the journal box.

45 50 In Fig. 3, the resilient core 16 is shown generally elliptical in form, which is very satisfactory for making a reversible packing package that may be used, first, with the side shown uppermost in Fig. 3 against the axle journal, and later reversed to bring the other side against the journal.

55 For packages not to be reversed, the core and consequently the package are shaped more nearly like a bow or semi-elliptical and of size suitable for filling the space between the lower side of the journal and the bottom and adjacent sides of the oil cellar.

60 65 Carding machines and waste pullers delivering a layer of carded waste substantially uniform have long been familiar. Machines for hooking the waste to the fabric are known.

As the layer or layers of waste and fabric go through a hooking machine, they pass over a hooking plate, where they are subjected to the action of a multitude of hooked needles reciprocating up and down.

The carding machine delivers the layer of waste in substantially uniform thickness and with the waste threads extending generally lengthwise to the layer, although the natural wave of the threads makes them depart from strict parallelism to the direction in which the sheet is delivered.

70 75 As the layer of waste and fabric go through the action of the hooked needles, many of the waste threads are caught by the hooks and pulled downwardly in loops

through the remainder of the layer of waste and through the fabric, and formed into loops below the fabric. In some instances, the waste threads will be caught near the top of the layer—in others, deeper into the layer—but the overall effect is to hook individual threads of waste through the mass of waste and the fabric and not only fasten those particular threads but associated threads into a blanket in which, generally speaking, all the threads are made fast against being pulled out in service.

During this hooking operation with waste and open weave cotton like laundry bag cloth, the weave is tightened or shrunk by the interlacing of the threads which are thereby brought into intimate contact with the threads of the cloth in such a way as to promote ready transfer of oil from the cloth to the waste threads.

The number of needles, the spacing of the needles, and the number of passes through the blanket per unit of length determine how thoroughly the threads of waste are interlaced through the blanket from side to side.

In many instances, the loops pull through the fabric or interlace below so as to actually knit the whole together.

In Figs. 4 and 5, 17 indicates a relatively thick layer of waste interlaced with a woven carrier cloth 18 and a relatively thin layer 19 of waste. The three layers are thoroughly fastened together by the interlacing of waste threads. The thinner layer 19 may be formed entirely by hooking threads through the fabric from the thicker layer 17, and it can be in part formed by feeding a thin layer of carded waste under the carrier cloth before reaching the hooking machine or in a supplementary or preliminary hooking machine. The relative thickness of the two layers of waste is a matter of choice.

The specifications for new waste for journal box packing issued by the Association of American Railroads requires that the waste be double machined and thoroughly delinted to remove "fly and short ends." Those things, together with the specifications for quality and minimum length, insure that the laminated blanket shown in Figs. 4 and 5 is composed in the main of waste as specified so interlaced in the several laminations that each and every thread of that waste is made fast, and the entire blanket is free from objectionable lint and short ends. The use of such a laminated blanket in a packing as described insures that, no matter what the weather conditions, there is only a remote chance of the journal being able to pull a portion of the thread from the applicator and take it under the journal bearing. This distinguishes the packing of the present invention from the prior packing that has been in common use for many years with the attendant objections.

However, according to this invention, the inner or lower side of the thinner layer of waste is preferably treated with an adhesive 20 to fasten at the under side of the blanket all threads that go through to the under side of the blanket.

In addition, that adhesive forms a sort of pan or basin under the journal for a reservoir of lubricating oil that will not drain away while the car is still for a considerable period.

That adhesive may be made of any appropriate material, many of which are known as rubber-base cements. They may be used in powder form, sheet form, or liquid. Many of the so-called synthetic rubbers are appropriate—for example, synthetic rubber made from petroleum by B. F. Goodrich Chemical Company, Akron, Ohio.

Hycar latex No. 1552, type OR-25, thickened with about 12% ammonium casein solution is very satisfactory.

Hycar 1561 type OR-15 latex has superior resistance to oil, and provides a more uniform layer, which does not penetrate the blanket unduly.

Other suitable synthetic rubbers are described in Materials Handbook by Brady, 1941, McGraw-Hill, p. 523.

In Figs. 4 and 5, the blanket is provided with an additional fabric 21, and the adhesive layer is applied to that fabric as well as the interlaced threads.

This further insures that the adhesive will not penetrate so far into the blanket as to interfere with the proper capillary action. When properly applied, the adhesive is confined to the lower side of the waste layer 19 and the fabric 21.

Leno weave netting, commonly known as onion-bag material, has been found satisfactory for the supplemental fabric 21. Alternative material made from sisal fibers is also good.

The supplemental fabric adds materially to the strength of the blanket and enables the lubricator to hold its shape for extended periods of time in rough service in the journal box. The addition of the supplementary cloth also permits a much more uniform film of adhesive to be applied to the back of the blanket, effecting a saving in the costly Hycar material.

Preferably the applicator surface of the waste package has the threads running generally parallel to the axis of the journal with which it is to be used, so that when the journal is reversed in direction of rotation there is some turning of the threads that presents new surfaces to the journal and retards or eliminates glazing.

The use of the laminated blanket, such as described, keeps the waste in place and makes it possible to use a smaller quantity of waste than required when the journal box is packed as recommended by the Association of American Railroads.

About 14½ ounces of laminated waste blanket is sufficient for a package to be used in a 6" x 11" journal box, whereas the ordinary way of packing such a package takes about two pounds of waste.

The resilient core

The resilient core can be made of a variety of materials and many different constructions, but all are characterized by having a plurality of parallel contiguous tubes of oil-resistant, rubber-like material arranged in what may generally be termed a honeycomb.

In Fig. 6, there is illustrated a core 30 composed mainly of a stack of like parallel, circular tubes 31 vulcanized together at adjacent surfaces 32. This core is conveniently made by extruding the tubes simultaneously or separately, bringing them together while uncured, and curing them. The tendency to collapse can be controlled by injecting air or other fluid under pressure.

In Fig. 7, there is illustrated a core 33, also composed mainly of a stack of like parallel tubes, but in this instance each tube has wall portions in common with other tubes 34 and integral with them at the adjoining corners 35. This core is conveniently made by extruding in one piece, whereby the cellular structure is entirely integral and the distribution of material makes it possible to have an extremely light, springy element with a strong resistance to deforming under pressure and a high recovery upon release, even after being compressed for a long time under adverse temperature conditions.

Cores corresponding to that shown in Fig. 7 can be made in a great variety of forms. Almost any polygonal form can be thus extruded, whether regular, irregular, right angular, or otherwise.

Of the many polygonal and generally polygonal forms which may lend themselves to the application of the invention, the equilateral hexagon is chosen because it lends itself so readily to making cores, and it has a structure particularly adapted for this purpose. Its springiness is very well suited to the needs of holding the applicator against the journal in spite of all the vibration, presence of oil, cold, and other conditions that obtain in the journal box.

The production of the extruded core is the subject of a companion application, Ser. No. 418,442, filed March 24, 1954, the disclosure of which is incorporated herein

by this reference. The material used is an oil-resistant, rubber-like material, such as Hycar, a product of B. F. Goodrich Co. of Akron, Ohio.

In Fig. 11, there is illustrated another form of resilient core 36 composed mainly of parallel tubes 37 of polygonal cross section having common walls and integral at the intersections or corners 38 of those walls. It is readily extruded.

The extruded cores may be, and preferably are, made in one piece; and they are preferred to the form shown in Fig. 6 because of the different strength qualities as well as the ease of manufacture.

One of the advantages of the multi-tubular core is the fact that the packing assembly, when subjected to a transverse force, compresses easily and fully to a small dimension, but does not bulge sidewise on application of endwise pressure when, for instance, the packing is being inserted into the journal box.

There are several reasons for this desirable trait. For one thing, the tubes of the cores extend longitudinally of the lubricator and are made up of relatively thin walls. As shown in the drawings, the resilient material forming the walls is substantially uniformly distributed over the total space occupied by the core in its unstressed position, and actually occupies a relatively small percentage thereof. This permits the core to be compressed almost flat, for instance, to less than one-tenth of its size; and yet it takes no set.

The longitudinally extending tube construction of the core is significant for another reason. When a packing containing the core is installed in a journal box, the relatively small space between the end flange of the journal and the front of the journal box (see, for instance, Figure 2) requires that the end of the core take a substantial portion of this pressure. The longitudinally extending interconnecting walls of the core prevent the material forming the core from bulging outwardly at the sides and edges of the core under this endwise pressure against the core. This permits the packing to slip into place without having to jack the box, contrary to practice when installing most lubricators.

The reason for this appears to be that endwise pressure on the interconnecting walls places the walls under offsetting tension and compression forces, thereby eliminating the tendency of the outer surface of the core to bend or bulge sidewise of the packing. Referring to Figure 7, for instance, application of endwise pressure to one of the three walled corners 35 may place two of the walls in compression and the third wall in tension, or vice versa, whereby the tendency of the corner 35 to buckle under endwise pressure is resisted. This makes the core relatively stiff longitudinally (which may be called columnar rigidity), but permits the sidewise springiness required to press the packing applicator surface against the journal.

Fastening the envelope to the core

It is necessary to fasten the resilient core in the laminated envelope 13, and, while this may be done in a variety of ways, it is simply and effectively accomplished by using a strip or strips of cloth tape 40 (Fig. 9) cemented or vulcanized to the core at 41 (Fig. 8), and sewed, cemented, or vulcanized to the end portions of the laminated envelope at 42. The showing in Fig. 8 is, of course, diagrammatic and distorted to indicate a long area of contact between the strip 40 and the core and end contacts between the strip and the envelope. In one form that has been found satisfactory, one strip above and another below are sufficient.

Handle or strap

When the package embodying this invention is to be put to use, it is compressed and worked down under the journal into the position shown in several of the figures. Once in that position, the resilient core holds

it in place and prevents it from working out of the correct position.

In order to make it easy to remove the package from the journal box, it is provided with a strap 44 (Fig. 10) 5 fabricated of oil resisting rubber-like materials and canvas or jute webbing, and made fast to the lubricator package substantially throughout the length of the latter and extending well toward the entrance to the journal box, as illustrated in Fig. 2, where it is provided with an opening 45 to receive a hook similar to that ordinarily found on the box packer's tool and by which the entire package may be withdrawn from the journal box.

In order to insure that the strap 44 is sufficiently flexible to bend as the package is put into or pulled out 10 of the outer position, its lower surface is provided with a series of notches or grooves 46.

The projecting portion of the strap 44 is provided on 15 its upper side with a legend giving the size of the journal box in which it is to be used, and directions "This side up"; and it may be well to also mark the other side "Bottom."

In the cross section shown in Fig. 12, the lubricator 20 package includes an envelope 13 with a core 30 corresponding to that shown in Fig. 6, in which the tubes are 25 distorted due to the compression necessary in the restricted space between the lower side of the journal and the bottom of the journal box.

In the cross section shown in Fig. 13, the lubricator 25 package includes an envelope 13 and a resilient core 33 corresponding to that shown in Fig. 7 distorted for the 30 reasons indicated above.

In both Figs. 12 and 13, the strap or handle 44 is 35 shown as secured to the outside of the envelope 13 at the bottom, which may be done by vulcanizing, stitching, or both, or any other suitable means.

In the cross section shown in Fig. 14, the package 40 includes an envelope 50 corresponding to the envelope 13 on the upper side, but having no waste attached to the lower portion 51. Instead, the carrier cloth 18 is 45 left bare and long enough to extend from the area indicated by 52 to the middle of the box and back to 52 again. In other words, the laminated portion of the basic material has a sort of selvage of the woven fabric 18 wide enough to fold and extend from the area 52 to the middle of the box.

This construction has the advantage of using less 50 cotton waste and leaving the capillary action of the woven material free from any diverting flow that might occur in the form shown in Figs. 12 and 13, to the end that the lift of oil charged into the oil cellar is more rapid than when the envelope has waste all the way around.

In Fig. 14, the strap 44 is shown attached to the upper 55 side of the envelope at the bottom of the package and overlapping the joint between the two sides of the selvage to which it is secured by vulcanizing, stitching, or both, or otherwise.

Fig. 15 corresponds to Fig. 14 except that the core 33 corresponds to that shown in Fig. 7 instead of that 60 shown in Fig. 6.

In one form that has been found satisfactory, the 65 resilient core is composed of 58 hexagonal tubes on the order of $\frac{1}{16}$ " in size with wall thickness on the order of .020".

The strap 44 is approximately $\frac{3}{16}$ " thick by 2" wide, and stiffer than belting of those dimensions. It is molded to fit the contour of the bottom wall of the journal box substantially as shown in Fig. 2 and assists in holding the package in place.

The strips 40 are 2 $\frac{1}{2}$ " nylon webbing 20 mils thick with a tensile strength on the order of 1200 pounds.

This application is a continuation-in-part of my 70 applications Serial No. 345,552, filed March 30, 1953, now Patent No. 2,747,952, and Serial No. 367,321, filed July 10, 1953, now Patent No. 2,762,667.

I claim:

1. In a lubricator for a car journal adapted to be mounted in a journal box and rest upon the floor of the oil cellar therein, the combination of a resilient core, an oil-absorbent material mounted on the top side of the core and adapted to be resiliently pressed into contact with the car journal by said resilient core, and capillary means for lifting oil from the oil cellar to said oil-absorbent material, said core being made of oil-resistant, rubber-like material and comprising a plurality of parallel tubes arranged in contiguous relation to provide a honeycomb structure, the depth of said tubes being many times greater than the thickness of the tube walls, whereby the core may be compressed vertically to a small fraction of its free height to facilitate the ready insertion and removal of the lubricator from the journal box.

2. A lubricator as set forth in claim 1 in which the core is an extruded member having a single wall thickness between the contiguous tubes.

3. A lubricator as set forth in claim 1 in which contiguous tubes have common walls having a wall thickness on the order of about .020" and with the depth of the tubes being on the order of $\frac{1}{16}$ ".

4. A lubricator as set forth in claim 1 in which said capillary means is looped about the core and comprises a woven cloth of capillary material having its ends positioned adjacent each other at the bottom of the lubricator, and a strap overlapping and secured to the contiguous ends of said cloth, said strap extending forwardly of the capillary means to form a handle.

5. In a lubricator for a car journal adapted to be mounted in a journal box and rest upon the floor of the oil cellar therein, the combination of a resilient core, an oil-absorbent material mounted on the top side of the core and adapted to be resiliently pressed into contact

with the car journal by said resilient core, capillary means for lifting oil from the oil cellar to said oil-absorbent material, and a relatively stiff strap secured to substantially the entire length of the lubricator and extending forwardly thereof to provide a handle for removing the lubricator, said strap being provided with transverse notches along a portion of its secured length to facilitate bending of the strap in the area of the notches during the insertion and removal of the lubricator from the journal box.

10 6. A lubricator as set forth in claim 2 in which the tubes are of hexagonal cross-sectional shape.
